UNITED STATES PATENT OFFICE

159,329

TRAFFIC SIGNAL FOR A DIVIDED HIGHWAY

Robert O. Ferguson, Bristol, Tenn., assignor of
one-half to Bristol Steel & Iron Works, Inc.,
Bristol, Va., a corporation of Virginia

Application March 10, 1949, Serial No. 1,346

Term of patent 14 years

(Cl. D72—1)

To all whom it may concern:

Be it known that I, Robert O. Ferguson, a citizen of the United States and a resident of Bristol, in the county of Sullivan and State of Tennessee, have invented a new, original, and ornamental Design for a Traffic Signal for a Divided Highway, of which the following is a specification, reference being had to the accompanying drawing, forming part hereof.

In the drawing, the single figure is a front elevational view of a traffic signal for a divided highway showing my new design, the dotted lines being for illustrative purposes only.

The device is substantially thin and flat and the back thereof is conventional.

I claim:

The ornamental design for a traffic signal for a divided highway, as shown and described.

ROBERT O. FERGUSON.
